UNITED STATES PATENT OFFICE.

ARNOLD BOHNENBLUST, OF RILEY, KANSAS.

SUCTION FORCE PUMP.

Application filed November 14, 1927. Serial No. 233,214.

This invention aims to provide a pump which will wear stuffing boxes to a minimum extent, the pump always being adequately primed, leakage past the pistons being taken care of, and a compact and effective structure being the result.

It is within the province of the disclosure to improve generally and to enhance the utility of devices of that type to which 10 the invention appertains.

With the above and other objects in view which will appear as the description proceeds, the invention resides in the combination and arrangement of parts and in the 15 details of construction hereinafter described and claimed, it being understood that changes in the precise embodiment of the invention herein disclosed may be made within the scope of what is claimed, without departing from the spirit of the invention.

In the drawings:—

Figure 1 shows in end elevation, a device constructed in accordance with the invention;

Figure 2 is a vertical section on the line 2—2 of Figure 3; and

Figure 3 is a longitudinal section on the line 3—3 of Figure 1.

30 The pump forming the subject matter of this application includes a frame made up of a base 1 and a casing 2 superposed on and connected to the base. The casing 2 has aligned cylinders 3, spaced apart, and connected by an enlarged compartment 4. An inlet manifold 5 extends lengthwise of the cylinders 3 and along the compartment 4. The manifold 5 has an inlet 6. An outlet manifold 7 extends lengthwise of the inlet manifold 5. The manifold 7 has an outlet 8. The ends of the outlet manifold 7 are separated from the ends of the inlet manifold 5 by L-shaped chambers 9 communicating with ports 10, the ports 10 being in communication with the cylinders 3 at points closely adjacent to the outer ends of the cylinders. First valves 11, which are slidably mounted, control the passage of liquid from the inlet manifold 5 to the chambers 9. Slidably mounted second valves 12 control the flow of liquid from the chambers 9 to the outlet manifold 7. The valves 11 close toward the inlet manifold 5, and the valves 12 close toward the chambers 9. The usual air chambers 14 are mounted on the casing 1 and communi-

cate with the outlet manifold 7 at points near to the ends of the outlet manifold.

Pistons 15 are mounted for reciprocation in the cylinders 3 and are united by a connecting rod 16. One end of a link 17 is pivotally connected at 18 with the rod 16, and the opposite end of the link 17 is pivotally connected at 19 with a radius arm 20 located in the compartment 4 and secured to a shaft 21 extended across the compartment 4 and mounted to rock in stuffing boxes 22 carried by the sides of the casing 2. Crank arms 23 are secured to the shaft 21 and are located externally of the casing 2. The 70 crank arms 23 are pivoted at 25 to pitmen 24 which, in their turn, are pivotally connected at 26 to gear wheels 27, eccentrically of the said gear wheels, the gear wheels being supported for rotation on the casing 2 75 at one end thereof. Gear wheels 27 mesh with pinions 28 on a transverse shaft 29 journaled for rotation in bearings 30 mounted on one end of the base 1. Rotation may be imparted to the shaft 29 in any suitable 80 way, for instance, by means of a pulley 31 on the shaft.

The numeral 32 marks a U-shaped conduit including a long arm and a short arm. The long arm of the conduit 32 is mounted 85 in the wall that exists between the compartment 4 and the inlet manifold 5. The conduit 32, therefore, establishes communication between the compartment 4 and the intake manifold 5. In the short arm of the conduit 32 there is a seat 33. A valve 34 is adapted to cooperate with the seat 33, the valve being carried by a stem 35 that is slideable in a bracket 37 mounted on the wall between the compartment 4 and the inlet 90 manifold 5. The stem 35 carries a float 36 located within the short arm of the intake conduit 32.

In practical operation, when rotation is imparted to the shaft 29 by means of the 100 pulley 31 or its equivalent, the pinions 28 will rotate the gear wheels 27, and from the gear wheels, motion is transmitted through the instrumentalities of the pitmen 24 to the crank arms 23 and to the shaft 21, a rocking 105 movement being imparted to the shaft. Owing to the fact that the parts 28—27—24—23 are duplicated at each side of the pump, true and even rocking motion is imparted to the shaft 21, and little if any difficulty is experienced in keeping up the stuffing boxes 22, the stuffing boxes operating 110

effectively for long periods, without much effort, and without renewal.

When the shaft 21 is rocked as aforesaid, swinging movement is imparted to the radius 5 arm 20, and the link 17 imparts reciprocation to the pistons 15 by way of the connecting rod 16, the pistons 15 sliding in the respective cylinders 3.

Considering the right hand cylinder in 10 Figure 3 of the drawings, it may be stated that when the corresponding piston 15 moves to the left, liquid is sucked through the inlet 6 and the inlet manifold 5, the valve 11 at the right hand end of Figure 3 15 opening to permit the liquid to pass into the corresponding chamber 9, the liquid moving into the cylinder 3 through the port 10. When, however, the right-hand piston 15, in Figure 3, moves to the right, the valve 11 20 closes, and the valve 12 thereabove opens.

Then the piston 15 forces the liquid out through the port 10, the chamber 9, the manifold 7, and the outlet 8.

Some liquid must necessarily pass through 25 into the compartment 4, past the pistons 15, or, considered from a different view point, the manufacturer may not care to attempt to give the pistons 15 an exceedingly tight fit in the cylinders 3. In either event, water 30 will accumulate in the compartment 4. When the pistons 15 reciprocate, a small quantity of water will be sucked through the conduits 32, from the compartment 4 into the inlet manifold 5. The pump, thus, will

be kept primed. When the level of the 35 water in the compartment 4 falls sufficiently, the float-operated valve 34 will rest on the seat 33, and there will be no flow of useless substance through the conduits 32.

What is claimed is:—

40 A pump comprising spaced cylinders and a compartment connecting the cylinders, an inlet manifold extended along the compartment and the cylinders, an outlet manifold 45 extended along the inlet manifold, chambers communicating with the cylinders and with the inlet and outlet manifolds, check valves controlling the passage of liquid from the inlet manifold to the chambers and closing toward the inlet manifold, check valves controlling the passage of liquid from the chambers to the outlet manifold and closing toward the chambers, connected elements 50 comprising pistons slidable in the cylinders, means for joining the pistons together, mechanism assembled with one of said connected elements for reciprocating the pistons, a priming conduit establishing communication between the compartment and the inlet manifold, and a float-operated 55 valve controlling the flow through the conduit and responsive to changes of liquid level in the compartment.

55 In testimony that I claim the foregoing as my own, I have hereto affixed my signature.

ARNOLD BOHNENBLUST.
